GOLF CLUB

Arthur J. Chapman, Wheeling, W. Va., assignor
of three-tenths to Charles I. Eshleman and
two-tenths to Robert B. Ryland, both of
Wheeling, W. Va.

Application February 10, 1939, Serial No. 255,605

4 Claims. (Cl. 273—77)

This invention relates to golf clubs, and more specifically to a golf club intended for practice in swinging the club.

An object of the invention is to provide a practice golf club equipped with a weight which travels from a position on the shaft between the head and the handle or grip of the club to a position at or near the head while the club is being swung, as a club would be swung in striking a ball, so as to give the operator a feeling somewhat similar to the feeling he would have in striking a ball, although no ball be used.

Another object is to provide a device of the character mentioned, intended for use by experienced golfers as well as those learning the game, which may be used to learn and obtain proficiency in the best manner of swinging the club, and especially in the so-called "follow through" of the club.

Another object is to provide a club of the character mentioned which will be useful and effective in teaching players the best method of raising the club over the shoulders to begin the swing, after the player has taken his stance.

A still further object is to provide a club of the character mentioned which is simple in construction and economical in manufacture.

And a still further object is to provide a device of the character mentioned having a stop adjustable upon the shaft so as to permit the travel of the weight to be lengthened or shortened at will and with a minimum amount of adjustment, so that the requirements of various users of the club may be readily met.

In describing the invention in detail, reference will be made to the accompanying drawing, in which—

Fig. 1 is a side elevation of a golf club embodying the invention;

Fig. 2 is a view partly in top plan and partly in cross section, taken on the line 2—2 of Fig. 1;

Fig. 3 is a view partly in side elevation and partly in vertical section of the weight and stop, taken substantially on the line 3—3 of Fig. 2;

Fig. 4 is a vertical sectional view of the head of the club; and

Fig. 5 is a top plan of the head.

In said drawing, in which like designating characters distinguish like parts throughout the several views, the numeral 11 indicates a rod-like shaft or staff, bearing at its upper end a conventional grip or handle 12. The lower end of said shaft is snugly received within a ferrule 13 formed integral with the upwardly directed portion 14 of a plate 15. A head 16 of conventional

form is affixed to said plate, as by screws 17. The portion 14 of the plate 15 extends upwardly from the bottom of the plate and is recessed underneath so as to permit a screw 18 to be directed upwardly through said plate and into the lower end of said shaft, whereby said shaft is held firmly in place within said ferrule. Manifestly, the ferrule, in addition to affording a guide for centering the shaft over the aperture 19 in the plate-portion 14 through which the screw 18 extends, also stiffens and strengthens the joint between the shaft and head portion of the club, represented generally by the letter A.

Said plate-portion 14 has shoulders 20 formed upon the upper surface thereof, and a cushion 21 15 of cylindrical shape and formed of resilient material, such as rubber, surrounds said ferrule and seats upon said shoulders 20.

Encircling said shaft between the grip 12 and the head portion A is a split sleeve 22 adjustable upon said shaft by means of a thumb-screw 23 in a manner which will be readily understood. Said sleeve has affixed thereto, preferably opposite said thumb-screw, a downwardly directed leaf spring 24.

Also slidably encircling said shaft 11 between the head portion A and the sleeve 22 is a weight 25, annularly grooved at 25a, and having its lower end broadened to form an annular seat 25b whose surface conforms substantially with the upper surface of the cushion 21. And the lower portion of said weight is annularly recessed or bored, at 25c, the diameter of said recess being slightly greater than the outside diameter of the ferrule 13, and the depth of said recess being somewhat greater than the height of said ferrule 13 above the upper portion of the cushion 21, so that no part of said weight will strike said ferrule when said weight 25 slides down said shaft 11 and strikes said cushion 21.

The spring 24 may have several leaves (as shown) or may be formed of only one leaf, and in either event the lower portion of the inner leaf is inwardly arched, as shown at 24a, so as to seat within the groove 25a of the weight 25, and thus to hold said weight in the position shown in Figs. 1 and 3 against the pull of gravity. The strength of said spring, however, is not sufficient to retain said weight in said position against the centrifugal force created by the swinging of the club as if one were striking a golf ball. On the contrary, when the club is so swung, with the weight placed in its raised or initial position illustrated in Figs. 1 and 3, the centrifugal force generated by the swinging of the club, will re-

lease the weight from the grip of the spring 24, allowing it to travel upon the shaft 11, to the position illustrated in dotted lines in Fig. 4. Said last-mentioned position (if the sleeve 22 has been 5 properly adjusted upon the shaft 11) will be reached by the weight 25 at substantially the instant one would strike a ball, if a ball were being used, and so gives the person using the club somewhat the same feeling he would experience 10 in striking a ball with a club not equipped with my invention. Furthermore, by reason of the increased weight at the head at the impact instant, the user more readily acquires the act of properly "following through" the stroke.

15 Furthermore, if a player has acquired the fault of whipping his club from a position behind the ball to the position over the shoulder at which the stroke is begun, the centrifugal force so generated will be sufficient, when using 20 a club equipped with this invention, to release the weight 25 from its initial position and force it to the head; but if raised gently, the weight will not be dislodged. A club equipped with this 25 invention is useful, therefore, in teaching golfers to overcome that fault.

The sleeve 22, as will be readily understood, affords a stop or barrier, limiting the upward movement of the weight 25, and the weight should always be placed in the initial position 30 shown in Figs. 1 and 3 before a stroke is begun. Such positioning may be accomplished either by manually sliding the weight to said position, or by raising the club overhead, with its head aloft, to the position from which a stroke is 35 begun, in which position the weight will slide downward along the shaft 11 by the force of gravity, and lodge in the initial position.

Manifestly, when the weight 25 reaches the cushion 21 during a rapid stroke of the club, the 40 cushion 21 will be depressed, and its outer walls forced outwardly. In order to permit such expansion of the cushion without causing undue strains upon the head 16, the surface of the latter lying adjacent to the cushion 21 is arcuately 45 grooved inwardly, as shown at 26 in Fig. 4.

Obviously, the distance the weight 25 should travel upon the shaft 11 so as to strike the cushion 21 at the proper point in the stroke of the club will differ for different users, and in 50 order that the club may be adapted to the stroke of various users, the sleeve 22, which fixes the upper limit of travel of the weight 25, is adjustable to any desired position upon the shaft 11, by means of the thumb-screw 23, as will be 55 readily understood.

Manifestly, this invention is adaptable to any type of club.

I claim—

1. A practice golf club comprising a shaft of substantially uniform diameter throughout its length, a head affixed to one end of the shaft, a ferrule affixed to the head and encircling the 5 adjacent end of the shaft, a resilient cushion encircling the ferrule, a weight encircling the shaft and slidably thereon between the cushion and a stop spaced away from the cushion, the weight having a seat designed to strike the cushion, and the head adjacent to the cushion being arcuately recessed away from the cushion so as to permit of expansion of the cushion when struck by the weight.

2. A practice golf club comprising a shaft of 15 substantially uniform diameter throughout its length, a head affixed to one end of the shaft, a ferrule formed integrally with a portion of the head and encircling the adjacent end of the shaft, a resilient cushion encircling the ferrule, 20 a weight encircling the shaft and slidably thereon between the cushion and a stop spaced away from the cushion, the weight having a seat designed to strike the cushion and being annularly grooved adjacent to the shaft so as to avoid 25 striking the ferrule, and the head adjacent to the cushion being arcuately recessed away from the cushion so as to permit of expansion of the cushion when struck by the weight.

3. A practice golf club comprising a shaft of 30 substantially uniform diameter throughout its length, a head affixed to one end of the shaft, a ferrule affixed to the head and encircling the adjacent end of the shaft, a resilient cushion encircling the ferrule, a split sleeve encircling 35 the shaft, a thumbscrew carried by the sleeve and adapted to hold the sleeve in binding position upon the shaft, the sleeve being adjustable upon the shaft with respect to the cushion, a weight encircling the shaft and slidably thereon between the cushion and the sleeve, a spring carried by the sleeve and designed to retain the weight adjacent to the sleeve until the club is 40 swung, the weight having a seat designed to strike the cushion, and the head adjacent to the cushion being arcuately recessed away from the cushion so as to permit of expansion of the cushion when struck by the weight.

4. In a golf club having a shaft and a head, a weight encircling the shaft and slidably thereon, a cushion encircling the shaft at the head and designed to soften the blow of the weight upon the head when the club is swung, the outer surface of said cushion being free to bulge outwardly when said cushion is struck by said 50 weight.

ARTHUR J. CHAPMAN.
